United States Patent Office

Des. 225,217
Patented Nov. 28, 1972

225,217

HOUSE

Joseph D. Yacoboni, 740 Olivant Place,
Pittsburgh, Pa. 15206

Filed Nov. 1, 1971, Ser. No. 194,806

Term of patent 14 years

Int. Cl. D25—03

U.S. Cl. D13—1

The figure is a perspective front view of a house embodying my new design; the rear view is substantially the same.

I claim:

The ornamental design for a house, as shown and described.
